United States Patent Office.

J. ZIMMER, JR., OF HALF DAY, ILLINOIS.

Letters Patent No. 96,860, dated November 16, 1869.

IMPROVEMENT IN HARNESS-PAD BLOCK.

The Schedule referred to in these Letters Patent and making part of the same.

To all whom it may concern:

Be it known that I, J. ZIMMER, Jr., of Halfday, in the county of Lake, and State of Illinois, have invented an Improved "Pad-Block;" and I do hereby declare that the following is a full and exact description thereof, which will enable those skilled in the art to make and use the same, reference being had to the accompanying drawings, and letters marked thereon, making a part of this specification, in which—

Figure 1 is a perspective representation of the pad-block, with the leather formed thereon

Figure 2, a perspective view of the same, with the leather removed.

Figure 3, a longitudinal section.

Figure 4, a transverse section.

The present invention relates to an improved means for forming harness-pads; and

Its nature consists in the use and application of a flexible-steel clamping-bow, which is operated, in combination with a pad-block and a screw, for the purpose of giving a more perfect form to a pad near the middle of the block, as the whole is hereinafter described.

A represents a wooden block, which is made to conform to the shape which the pad is to have when finished, a groove, C, being made in its edge, for the convenience of holding the clamping-bow D in place, and also, to turn the margin of the leather outward, for the convenience of stitching it to the back leather over the pad.

The clamping-bow D is made of spring-steel, in order that the leather formed over the block at the central part of the pad may be properly compressed, and its ends are turned outward for the purpose of fastening to links or chains, H.

This flexible bow is a very important part of the invention, as the long sides of the pad-block are frequently but little curved; hence, any ordinary chain or rope would not sufficiently clamp the leather to the central part of the block, to form a perfect pad.

The bow, however, should not be so stiff as to prevent it from being readily removed, to loosen the leather from the block when the pad is formed.

These links hook into a bar, G, which has a screw-thread in it, to receive a screw, F, with which the bow D is drawn closely into the groove C. A plate, B, being fastened to the end of the block A, provides a solid bearing for the end of the screw F, and the ends of the plate having notches, C, conforming to the shape of the groove C, holds the bow D in place, and prevents the wood at that end of the block from splitting, should the links draw the bow D more to one side of the block than the other.

To use this device, remove the hooks E E from the links H, and remove the bow D from the block A.

The leather I, fig. 1, is put on block A, and the bow D put over it, and drawn by screw F closely into the groove C.

The leather is then rubbed down, in the usual manner, and allowed to stand until the crimp is firmly set.

The crimping and forming leather over blocks is an art well known; nothing is, therefore, claimed in this regard, but the arrangement of parts herein mentioned is assumed to be new.

As to practical utility, a thorough test has proven that one man, with its aid, can perform at least the work of eight men using the ordinary means.

Having thus described my invention, I do not claim the forming of leather over blocks; but

What I do claim, and desire to secure by Letters Patent, is—

The flexible clamping-bow D; arranged to clamp the leather equally to the long sides of the block A, in combination with said block, the bar G, links H, screw F, and plate B, as set forth.

J. ZIMMER, JR.
